Application April 30, 1945, Serial No. 119,324

Term of patent 14 years

(Cl. D34—15)

To all whom it may concern:

Be it known that we, Benjamin H. Shapiro, Islyn Thomas and John Hohl, citizens of the United States and residents respectively of the city, county, and State of New York, town of Livingston, State of New Jersey and city of Newark, State of New Jersey, have invented a new, original, and ornamental Design for a Helicopter Pull Toy, of which the following is a specification, reference being had to the accompanying drawing, forming part thereof.

Fig. 1 is a plan view of a helicopter pull toy embodying our new design.

Fig. 2 is a side elevation thereof.

The side not shown on the drawing is substantially like the side shown.

We claim:

The ornamental design for a helicopter pull toy, substantially as shown and described.

BENJAMIN H. SHAPIRO.

ISLYN THOMAS.
